UNITED STATES PATENT OFFICE.

WALTER C. WILLARD, OF CLEVELAND, OHIO, ASSIGNOR TO THE FERRO MACHINE AND FOUNDRY COMPANY, OF CLEVELAND, OHIO, A CORPORATION OF OHIO.

CARBURETER.

No. 893,685.

Specification of Letters Patent.

Patented July 21, 1908.

Application filed November 19, 1906. Serial No. 343,967.

To all whom it may concern:

Be it known that I, WALTER C. WILLARD, a citizen of the United States, resident of Cleveland, county of Cuyahoga, and State of Ohio, have invented a new and useful Improvement in Carbureters, of which the following is a specification, the principle of the invention being herein explained and the best mode in which I have contemplated applying that principle so as to distinguish it from other inventions.

My invention, relating as indicated to improvements in carbureters, has regard more particularly to improvements in carbureters of the free-opening type.

The object of such invention is to provide a carbureter of this type that will be automatically compensating.

As is well known the method of speed control most generally employed in connection with internal combustion motors, involves diminishing the force of each impulse by admitting a smaller charge into the engine cylinder. In other words, the engine is simply throttled. This method of control obviously involves a corresponding variation in the amount of air passing through the carbureter in the course of forming a charge. Inasmuch as the suction effect at the hydro-carbon jet varies out of direct proportion to the amount of the air thus passing through the carbureter, it will be evident that in a free opening carbureter, difficulty is apt to be experienced in obtaining uniformly perfect mixtures. In the ordinary type of automatic carbureter many devices are employed to prevent the mixture varying in quality, chiefly consisting of auxiliary valves for admitting air, operated by the suction effect of the piston. Aside from the objection that more or less complication is involved in the structure of carbureters of this class, the additional objection is to be noted that their action is not fast enough for use with three-port two-cycle engines. The free-opening carbureter alone seems to be adapted for this service and it has been in an attempt to render such free-opening carbureter automatically compensating that the aforesaid improvements have been made. And I may state that I have obtained desirable and highly satisfactory results in this type of carbureter, by correlating, in a fashion to be presently set forth, the movements of the valve controlling the air-inlet of the carbureter with those of the throttle valve; such correlation further embodying a disposition of the valves in question whereby, when the amount of air passing through the carbureter is decreased, not only is the velocity, i. e., the amount of air passing through in a given time, maintained by corresponding decrease of the air inlet but the current of air that is allowed to pass through is directed across the fuel nozzle in such a way as constantly to have its maximum vaporizing effect.

In addition to the foregoing improvements, finally, my carbureter involves certain details of construction with the float chamber that enhance the efficiency of the means already mentioned. Said invention then consists of means hereinafter fully described and particularly set forth in the claims.

The annexed drawings and the following description set forth in detail certain means embodying the invention, such disclosed means constituting but one of various mechanical forms in which the principle of the invention may be used.

In said annexed drawings: Figure 1 is a plan view of a carbureter embodying my several improvements; Fig. 2 is a front elevation of the same; Fig. 3 is a vertical central longitudinal cross section of such carbureter; and Fig. 4 is a transverse cross section taken on a plane indicated by the line 4-4, Fig. 3.

The carbureter, chosen for the sake of illustration in the several figures of the drawings, comprises essentially an angular induction tube A, preferably formed with a flaring, bell shaped mouth a. Such angular induction tube is surrounded on the bottom and laterally on three sides by a float chamber B which has a bottom wall of substantially spherical conformation. Communication with such float chamber B is had by induction tube A by means of a fuel nozzle or jet C of the usual type, that projects into the angular portion of the tube to a point substantially on a level with that normally occupied by the fluid in float chamber B. Control of the flow of the fluid through such nozzle C is effected by means of a needle valve c of familiar form. The inlet or feed valve b of the chamber is located in a rearwardly projecting portion B' of the latter, that is suitably connected by means of a feed pipe B' with the feed tank or other source of supply. The type of valve controlling such feed is not

here an object of interest, that chosen for illustration being a needle valve normally gravity-actuated to close. Control of this feed valve b and thus of the fluid level in the float chamber is had through the employment of a float b' consisting of cork or other suitable material. Such float is of horse-shoe shape, in order that it may be conveniently disposed in the part of the chamber surrounding the vertical portion of the angular induction tube, as will appear upon inspection of Fig. 4. Operative connection between the float and feed valve b is had by means of a lever b^2 that is pivoted in suitable bearings intermediate of the float and feed valve. The rear end of lever b^2 is flattened and provided with an aperture adapted to receive the stem of the valve b , such valve being rendered adjustable with respect to the lever end by means of nuts b^4 threaded on the stem. A helical spring b^5 or equivalent resilient member surrounds the stem of valve b intermediately of such apertured lever end and the lowermost of nuts b^4 . The strength of this spring is gaged so as to permit of its compression upon any increase in the buoyant action of the float b' on lever b^2 upon the tilting of the carburetor or other similar change of position thereof. The object of this construction is to prevent flooding of the fuel nozzle C by a disturbance of the fluid level in the float-chamber such as would occur were the lever end not thus resiliently held and the float consequently made to displace more than its normal amount of fuel. The other end of lever b^2 is divided into two arms, such arms being sufficiently attenuated to give them a limited degree of elasticity which is utilized in effecting their engagement to the float. To this end the latter is provided on its upper face with two oppositely disposed eyes b^3 , designed to receive the outwardly turned ends of such lever arms. Such eyes b^3 are most conveniently provided by inserting small cotter pins in the float as will be readily understood. The line upon which the pins b^3 lie is chosen so as to pass through the center of buoyancy of the float. It will be seen that in all of the float's various movements, accompanying changes of level of the hydro-carbon in the chamber, its action on the lever b^2 will be perfectly balanced; furthermore, there will be much less likelihood of the lever's being improperly actuated by the float in case the carburetor as a whole is moved or rocked as is frequently the case in use on vehicles, motor boats and the like.

To revert now to the induction tube, it will be noted that a butterfly throttle valve A^2 for controlling the outlet opening of such tube is provided and a similar valve A' for controlling the entrance of air at the inlet opening of the tube. These two valves are connected by a suitable system of levers a' ,

and a^2 , and a link a^3 , shown diagrammatically in Fig. 3, in such a manner that the velocity of the air admitted through the air inlet opening of the tube is, in all positions of valve A^2 , regulated, other things being equal, to produce a substantially perfect mixture. Thus assuming both valves to be in the wide open positions indicated in dotted lines, it will be evident that the fuel nozzle or jet C can be regulated to provide just the right amount of fuel for making a perfect mixture. If now, however, the engine is running at a reduced rate of speed, as in starting or in a nearly closed position of the throttle A^2 , valve A' still remaining wide open, the velocity of the air will of course decrease. But the suction effect of the air at the jet, varying as has been stated out of direct proportion to such velocity, decreases much more rapidly than does the volume of air passing through the tube. An imperfect mixture, one poor in hydro-carbon, is a consequence followed by an ineffective explosion or even failure to secure any explosion at all. With the sort of connection between the valves, however, just set forth it will be evident that, under the conditions stated, the air inlet valve will have been automatically moved to a partially closed position when the engine has been throttled. Thus, in spite of the reduced amount of air flowing through the tube its full suction effect is maintained. The relative lengths of the levers and link shown in Fig. 3 for attaining this purpose have been chosen for use with one particular engine, viz., a three-port two-cycle engine and that in connection with the employment of the latter in marine work. For operation of a different type of motor and in a different situation, obviously the proportion of these parts might require to be changed. Such proportion of parts, however, is not intended to be adjustable once it has been determined. In other words the only adjustment of the levers contemplated as being possible in the completed carburetor is that of the initial angular position of the valves with respect to the levers a' and a^2 , respectively. This is secured by adjustably mounting the levers on the spindles a^4 of the valves in question, set-screw a^5 being provided for the purpose of securing the levers to such spindles when once the valves have been properly positioned; see Figs. 1 and 2, where the lever-ends only appear, the remainder being broken away.

I have found that the proportioning of the velocity of the air passing through the tube, as above explained, so that when the motor increases its speed the suction effect at the jet will nevertheless be maintained uniform, does not suffice to produce a perfect mixture unless the full effect of such air current on the jet or nozzle be realized. For when the air is thus reduced in quantity even though it ve-

losity be maintained, an insufficient quantity of hydro-carbon fuel is apt to be taken up unless the air is made to pass over the jet in such a fashion as to take up, or vaporize, all the hydro-carbon fed by the latter. To overcome this difficulty, then, I further so dispose valves A' and A^2 with respect to the axis of induction tube A as to cause them to incline similarly when in their partially closed positions, such direction of inclination being designed, as will be evident from an inspection of Fig. 3, to direct the current through said tube along its outer wall and hence across the fuel nozzle C . As a result of this disposition of the valves, I have found that the vaporizing effect of the air is made to correspond strictly with its suction effect, so that the fuel does not "drip" but is all carried into the cylinder and there used; and inasmuch as such suction effect is capable of regulation by means of the connection between the inlet valve A' and the throttle valve A^2 , it will be evident that by these two means I control absolutely the making of the charge, whether the engine is running at full speed or not or, in other words, whether a large or small charge is being admitted into the cylinder.

It will be understood, of course, that only a slight rearrangement of the parts just described would be required to adapt my improved carbureter to a situation requiring a horizontal instead of a vertical feed; or, for that matter, the tube may be made of reversible form whereby it may be used indifferently for horizontal or vertical feed according to the exigencies of the case.

By this method of control, while retaining all the advantages of the free opening carbureter, I secure the automatic compensating features that have heretofore characterized the auxiliary air-valve type of carbureter only. The chief of such advantages in the use of the free-opening carbureter is of course the fact that its rapidity of operation is limited only by that of the speed of the engine impulses, and hence it may be used with perfect satisfaction on the three-port two-stroke cycle engine. Obviously, the carbureter is equally adaptable to the requirements of the slower speeds of the four-cycle engine.

The structural features that I have set forth in connection with certain elements in the float chamber, I have found contribute materially to the successful operation of the carbureter under the trying circumstances attending its employment in motor boats and, to a slightly less degree only, on automobiles. For by the particular location of the fuel nozzle with reference to the fluid level in such float chamber, by the shape and disposition of the float itself and by the manner of suspension utilized in connecting the latter with the lever whereby it operates the feed valve of the chamber, I maintain a practi-

cally constant flow of fluid to a uniform height in the fuel nozzle or jet. This, added to the regulation which I effect of the air current and its suction effect on the nozzle, as I have demonstrated by actual experiment with my free opening carbureter, results in a large increase in the cylinder compression, power, and consequent efficiency of the motor, as well as in an excellent control and easy starting qualities.

Having thus described my invention in detail, that which I particularly point out and distinctly claim, is:

1. In a carbureter, the combination of an air induction tube, a fuel nozzle projecting into said tube, butterfly valves for controlling the inlet and outlet openings of said tube, respectively, and levers and a link connecting said valves whereby they are rendered operable in unison said valves being disposed to direct in their partially closed positions the current of air passing through said tube across said fuel nozzle.

2. In a carbureter, the combination of an air induction tube, a fuel nozzle projecting into said tube, butterfly air-inlet and throttle valves, and levers and a link connecting said valves whereby they are rendered operable in unison, said valves being disposed so as to incline similarly with respect to the axis of said tube when in their partially closed positions whereby the current of air passing through said tube is directed across said fuel nozzle, substantially as described.

3. In a carbureter, the combination of an angular air induction tube, a fuel nozzle projecting into the angular portion of said tube and from its outer wall, butterfly air-inlet and throttle valves, and levers and a link connecting said valves whereby they are rendered operable in unison, said valves being disposed so as to incline similarly with respect to the axis of said tube when in their partially closed positions and to direct the current passing through said tube along its outer wall.

4. In a carbureter, the combination of an air induction tube, a fuel nozzle projecting within said tube, butterfly air-inlet and throttle valves, a lever adjustably mounted upon the spindle of each of said valves, and a link connecting said levers, said valves being disposed so as to incline similarly with respect to the axis of said tube when in their partially closed positions whereby the current of air passing through said tube is directed across said fuel nozzle, substantially as described.

5. In a carbureter, the combination of an air-induction tube comprising two portions rectangularly related to each other, a fuel nozzle projecting into the angular portion of said tube and from its outer wall, butterfly air-inlet and throttle valves, and levers and a link connecting said valves whereby they are

operable in unison, said valves being disposed so as to incline toward such outer tube wall and in the direction of the flow of air therethrough so as to direct the current passing through said tube along such outer wall when said valves are in their partially closed positions.

6. In a carbureter, the combination of an air-induction tube comprising two rectangularly related portions, a fuel nozzle projecting into the angular portion of said tube and from its outer wall, butterfly air-inlet and throttle valves, a lever adjustably mounted upon the spindle of each of said valves, and a

link connecting said levers, said valves being disposed so as to incline towards such outer tube wall and in the direction of the flow of air therethrough whereby the current of air passing through said tube is directed across said fuel nozzle when said valves are in their partially closed positions, substantially as described.

Signed by me, this 5th day of November, 1906.
